LOCOMOTIVE STOKER

John W. Myers, Roanoke, Va., assignor to The Standard Stoker Company, Incorporated, a corporation of Delaware

Application February 5, 1932, Serial No. 591,127

10 Claims. (Cl. 198—15)

This invention relates to improvements in locomotive stokers of the scatter feed type in which feed is conveyed from the fuel bin to the firebox firing opening, the invention being particularly directed to improvements in the fuel conveying system thereof.

The principal object of this invention is the provision of a stoker fuel transfer conduit fixedly mounted on the tender with respect to vertical and longitudinal movement and pivotally mounted for lateral movement with reference to a vertical axis.

It is the further object of this invention to provide, in a stoker having a transfer conduit disposed on the tender as described, a novel arrangement of the fuel conveying system which consists in universally jointing one end of an extensible intermediate conduit to a riser conduit secured to the backhead and connecting the opposite end of the extensible intermediate conduit to the fuel transfer conduit in a manner so that the intermediate conduit is permitted to swing upon a transversely extending axis. By these provisions, ample flexure of the fuel conveying system is attained to provide for angular displacement and longitudinal movement between the locomotive and tender while rounding curves or passing over "cross-overs" and turntables.

Other objects and advantages derived from the invention reside in certain improvements of details as will appear in the specification and in the drawing annexed thereto, in which

Fig. 1 is a central vertical longitudinal section through adjacent portions of a locomotive and its tender, showing the invention partly in section and partly in elevation;

Fig. 2 is a sectional view taken on the line 2—2 of Figure 1; and

Fig. 3 is a fragmentary view similar to Figure 1 showing a modified form of the invention.

Referring to Figures 1 and 2, the locomotive is designated by the letter A, its tender by B and a coupling member therebetween by C. The locomotive is provided with a firebox 10, a backhead 11 having a firing opening 12 therethrough and a cab deck 13 extending rearwardly of the backhead. The tender includes a fuel bin 14 having its deck 15 centrally apertured as at 16 through which fuel may fall by gravity into the open mouth fuel transfer conduit 17 of the fuel conveying system S, as controlled by the shiftable plates 18.

The transfer conduit 17 includes a trough 19 having a saddle member 20 formed rigidly therewith intermediate its ends for supporting the

transfer conduit from the frame 21 of the tender B. Depending from the underside of the saddle member 20 is a foot plate 22 which rests upon the horizontal portion 23 of the support bracket 24, rigidly secured to the tender frame 21. A vertically disposed shaft or pin 25 passes through the foot plate 22 of the saddle member 20 and the horizontal portion 23 of the support bracket, the pin preferably passing freely through these portions so that the transfer conduit may have a free lateral motion about the pin 25 without permitting any longitudinal movement thereof with respect to the tender. The outer extremities of the shaft or pin 25 are provided with the threaded caps 26 and 27 whereby they may be adjusted so that the adjacent faces of the foot plate 22 and of the horizontal portion 23 may be maintained constantly in a contacting relation, thereby preventing any vertical movement of the transfer conduit. The trough member 19 may be further supported by pedestals such as 28 which may be secured either to the support bracket 24 as shown, or to the tender frame 21, the trough 19 being free to slide upon this pedestal.

Secured to the front wall 29 of the trough 19 is a connecting member 30 which has a tubular section 31 thereof communicating with the opening 32 in the front wall 29. The forward extension of this connecting member is substantially U-shaped in vertical transverse cross section, having the parallel sidewalls 33, 34 and the arcuate shaped bottom 35 which is also of similar form in its vertical longitudinal section. The forward extension of the connecting member 30, may, if desired, be provided with a top wall 36 which has an enlarged section 37 to receive a horizontal, transversely extending, shaft 38.

Depending from the extremities of the shaft 38 by its sidewalls 39, 40, is the rearward portion 41 of the intermediate conduit section 42 which serves to connect the riser conduit 43 of the locomotive and the transfer conduit 17. The portion 41 is also U-shaped in vertical transverse cross section and has its sidewalls 39, 40 and its bottom arcuate wall 46 in intimate parallel relation with the corresponding walls of the connecting member 30. Thus, the intermediate conduit may swing upon the horizontal, transversely extending shaft 38 without loss of fuel.

Forwardly of its rearward portion 41, the intermediate conduit section 42 is circular in transverse vertical section, upon the forward end 47 of which is slidably mounted a spherical segment 48. The lower portion of the riser conduit 43 terminates below the cab deck 13 in a spherical

seat 49, which, together with the spherical segment 48 and a split clamp 50, forms a universal connection 70 between the riser conduit 43 and the intermediate conduit 42. The riser conduit 43 inclines forwardly from this connection and delivers fuel through the firing opening 12 of the backhead 11 to which the riser conduit 43 is rigidly secured as by means of the support bracket 51. The upper end of the riser conduit forward 10 wall 52 extends into the firing opening and supports a pressure fluid head 53 which serves to project fuel over the firebed from the distributing table 54 as delivered thereto by the riser conduit 43 of the conveying system S.

15 Suitable means for advancing fuel through the conduits are provided and include a screw conveyor 55, the rearward portion 56 and the forward portion 57 of which are universally connected as at 58, at the joint between said transfer 20 conduit 17 and said intermediate conduit 42. The conveyor screws are driven in the usual manner, as by means of a motor connected to gearing at the rear of the trough 19, not shown.

In the modified form shown in Figure 3, a 25 screw 59 is mounted within the riser conduit 43, the screw 59 being universally connected as at 60, to the screw portion 57 of the intermediate conduit 42 and is supported at its forward terminus by a bearing 61. A threaded nut 62 engages the 30 shaft extension 63 of the screw 59 and maintains the screw within the riser conduit when the locomotive and tender are uncoupled. To provide for the relative longitudinal movement between the locomotive and tender, the screw portion 57 35 of the intermediate conduit 42 is comprised of the telescoping screw members 64 and 65, the member 64 having an angular extension 66 which is received by the angular recess 67 within the hub 68 of the member 65.

40 From the foregoing description, it will be seen that a fuel conveying system of novel form has been provided which is characterized by the improved means of mounting and relating the fuel conveying conduits one with another. The function 45 of the fuel conveying conduits, when the locomotive and tender are negotiating curves, crossovers or turntables, may be summarized as follows: the mounting of the transfer conduit 17 about the vertical pin 25 together with the universal connection 70, between the riser conduit 43 and the extensible intermediate conduit 42 allows for vertical, lateral and longitudinal movement in the conduit system. Since the transfer conduit 17 is rigidly mounted with respect to 50 longitudinal movement of the tender and movement with reference to a horizontal, transversely extending axis, the forward end 47 of the intermediate conduit 42 is in a telescopic slidable relation with the spherical segment 48 of the ball joint 70, while the rearward portion 41 of the intermediate conduit is jointed to the transfer conduit 17 so as to swing about the transverse shaft 38. Thus the fuel conveying system is organized 55 so as to provide ample flexure of its conduits to compensate for articulation between the locomotive and the tender. In the modified form, the function of the conduits is the same as in the preferred form. In this modified form, since the screw conveyor 55 is held in bearings 60 at its extremities, the screw section 57 is provided with a telescopic connection to provide for the movement between the locomotive and the tender.

75 I claim:

1. In a locomotive provided with a firebox hav-

ing a firing opening therein and a tender for said locomotive, a fuel conveying system comprising a transfer conduit fixedly mounted on said tender with respect to vertical and longitudinal movement thereof, and pivotally mounted intermediate its ends for lateral movements with reference to a vertical axis, a riser conduit attached to said locomotive and arranged to deliver fuel through said firing opening, and an intermediate conduit section flexibly connected at its ends to said 10 riser conduit and said transfer conduit.

2. In a locomotive provided with a firebox having a firing opening therein and a tender for said locomotive, a fuel conveying system comprising a transfer conduit fixedly mounted on said tender 15 with respect to vertical and longitudinal movement thereof, and pivotally mounted intermediate its ends for lateral movement with reference to a vertical axis, a riser conduit attached to said locomotive and arranged to deliver fuel through 20 said firing opening, and an extensible intermediate conduit section connecting said riser conduit and said transfer conduit, one end of said 25 intermediate conduit being jointed to said riser conduit and the other end thereof being jointed to said transfer conduit to swing upon a transversely extending axis.

3. In a locomotive provided with a firebox having a firing opening therein and a tender for said locomotive, a fuel conveying system comprising a transfer conduit fixedly mounted on said tender with respect to vertical and longitudinal movement thereof and pivotally mounted intermediate its ends for lateral movement with reference to a vertical axis, a riser conduit attached to said locomotive and arranged to deliver fuel through 35 said firing opening, and an extensible intermediate conduit section connecting said riser conduit and said transfer conduit, one end of said intermediate conduit being universally 40 jointed to one of said named conduits and the other end thereof being jointed to the other of said named conduits to swing upon a transversely extending axis.

4. In a locomotive provided with a firebox having a firing opening in the backhead thereof and a tender for said locomotive, a stoker comprising a transfer conduit fixedly mounted on said tender with respect to vertical and longitudinal movement thereof and pivotally mounted intermediate its ends for lateral movement with reference to a vertical axis, a riser conduit secured to said backhead and delivering through said firing opening, and an extensible intermediate conduit 50 section connecting said riser conduit and said transfer conduit, one end of said intermediate conduit being universally jointed to said riser conduit and the other end thereof being jointed to said transfer conduit to swing upon a transversely extending axis.

5. In a locomotive provided with a firebox having a firing opening in the backhead thereof and a tender for said locomotive, a stoker comprising a transfer conduit fixedly mounted on said tender with respect to vertical and longitudinal movement thereof and pivotally mounted intermediate its ends for lateral movement with reference to a vertical axis, a riser conduit secured to said backhead and delivering through said firing opening, an extensible intermediate conduit 65 section connecting said riser conduit and said transfer conduit, one end of said intermediate conduit being universally jointed to said riser conduit and the other end thereof being jointed to said transfer conduit to swing upon a trans- 70

versely extending axis, and screw means for advancing fuel through said conduits.

6. In a locomotive provided with a firebox having a firing opening in the backhead thereof and a tender for said locomotive, a stoker comprising a transfer conduit fixedly mounted on said tender with respect to vertical and longitudinal movement thereof and pivotally mounted intermediate its ends for lateral movement with reference to a vertical axis, a riser conduit secured to said backhead and delivering through said firing opening, an extensible intermediate conduit section connecting said riser conduit and said transfer conduit, one end of said intermediate conduit being universally jointed to said riser conduit and the other end thereof being jointed to said transfer conduit to swing upon a transversely extending axis, a screw in said transfer conduit and a screw in said intermediate conduit, said screw being universally connected adjacent their ends in coincidence with the joint between said transfer conduit and said intermediate conduit.

7. In a locomotive provided with a firebox having a firing opening in the backhead thereof and a tender for said locomotive, a stoker comprising a transfer conduit fixedly mounted on said tender with respect to vertical and longitudinal movement thereof and pivotally mounted intermediate its ends for lateral movement with reference to a vertical axis, a riser conduit secured to said backhead and delivering through said firing opening, an extensible intermediate conduit section connecting said riser conduit and said transfer conduit, one end of said intermediate conduit being universally jointed to said riser conduit and the other end thereof being jointed to said transfer conduit to swing upon a transversely extending axis, and a screw in each of said conduits, said screws being universally connected at their adjacent ends in coincidence with the joints in said conduits.

8. In a locomotive provided with a firebox having a firing opening in the backhead thereof and a tender for said locomotive, a stoker comprising a transfer conduit fixedly mounted on said tender with respect to vertical and longitudinal movement thereof and pivotally mounted intermediate its ends for lateral movement with reference to a vertical axis, a riser conduit secured to said backhead and delivering through said firing opening, an extensible intermediate conduit section connecting said riser conduit and said transfer conduit, one end of said intermediate

conduit being universally jointed to said riser conduit and the other end thereof being jointed to said transfer conduit to swing upon a transversely extending axis, screw means for advancing fuel through said conduits including a screw in said transfer conduit, a screw in said extensible intermediate conduit and a screw in said riser conduit, said screws being universally jointed at their adjacent ends in coincidence with the joints in said conduits, and a bearing for supporting and maintaining said riser conduit screw in its relation with the joint between said riser conduit and said extensible intermediate conduit, the screw in said last named conduit being comprised of telescopic screw members.

9. In a stoker for use with a locomotive having a tender and a fuel bin, a fuel transfer conduit mounted beneath the tender fuel bin, a bracket rigidly secured to said tender, said bracket being provided with a horizontal portion, a saddle member formed with said transfer conduit, said saddle member being disposed intermediate the ends thereof and having a foot plate depending therefrom and resting upon the horizontal portion of said bracket, and means for mounting said transfer conduit fixedly with respect to longitudinal and vertical movement of the tender and pivotally with respect to movement about a vertical axis, said means including a vertically extending shaft engageably passing through the foot member of said saddle member and the horizontal portion of said bracket, and means engaging said shaft whereby the adjacent faces of said foot member and said bracket horizontal portion are maintained in contact with each other.

10. In a locomotive and tender, the combination of a stoker feed conduit system comprising a forward riser conduit section rigidly secured on the locomotive, a rearward transfer conduit section fixedly mounted on the tender with respect to vertical and longitudinal movement thereof and pivotally mounted intermediate its ends for lateral movement with reference to a vertical axis, an extensible intermediate conduit section interposed between the named sections to form a continuous conduit, and means for attaching said extensible intermediate conduit section to the forward and rearward conduit sections to permit relative vertical, longitudinal and lateral movement between said forward and rearward conduit sections.

JOHN W. MYERS.
